SYSTEM OF PHOTOGRAPHY

Samuel Hershberg, Brooklyn, N. Y.

Application September 15, 1934, Serial No. 744,825
Renewed March 14, 1939

20 Claims. (Cl. 95—14)

This invention relates generally to photography, and more particularly to a system of photography whereby the lighting mechanism, the camera structure and development of the exposed sensitized material cooperate in a substantially automatic manner such that an artistic photograph results which heretofore could have been produced only in single operations by tedious hand means and by skilled operators.

10 The main object of this invention is the provision of a system of photography whereby an unskilled operator is enabled to produce a photograph of a quality comparable to that produced by a finished and experienced artisan, and where-
15 by a skilled and experienced artisan is enabled to produce more photographs in a given amount of time and of a better quality than heretofore, owing to a substantial reduction in manual manipulation of the lighting means, focusing and
20 adjustment of the camera and the development of the exposed photographic paper.

Another object of the invention resides in the provision of a system of photography whereby a finished proof is furnished to the patron within 25 a very short time after the sitting and with a complete elimination of the usual step of proof-making.

Another object of the invention is the provision of a system of photography whereby operating costs are reduced to a minimum owing to: saving of space by virtue of compact and cooperative arrangement of lighting unit, camera unit and developing unit; saving of power costs since bright illumination is used only during actual 30 exposure time; saving of sensitized material costs as high-speed papers may be used in conjunction with the high actinic power of the lighting unit; saving in the cost of chemicals by eliminating inter-tank pollution in the developing unit; saving of labor by substantially automatic manipulation in all three of the aforementioned units; the production of a higher average of perfect prints, the result of proper composition, accurate exposure, scientific lighting, precise timing of development and exact mechanical manipulation.

A further feature of the system of photography, the object of the invention herein, resides in the elimination of guess-work in lighting, composition, exposure and finishing and the substitution therefor of a predetermined scientific technique.

Another feature of the system rests in the substitution for the ordinary stand, of a new and unique type of stand embodying an inclined sta-
55 tionary runway so designed that as the camera

is moved along the runway to and from the subject, it is automatically raised or lowered in a vertical plane so that a proper level and tilt of the camera is maintained.

A still further feature of the system in the 5 lighting unit is the provision of a process whereby a change in the lighting of the subject to conform with a change in the position of the subject is readily accomplished. This process involves the mere aiming of one mirror directed 10 to the sitter which act of aiming automatically shifts the light so that it falls upon the subject in the proper direction and intensity.

The aforementioned objects and features of the system of photography together with other 15 incidental techniques and processes will herein-after more fully appear in the process of this disclosure.

Since the invented system of photography herein involves the cooperation of a developing 20 unit, a camera unit and a lighting unit, each unit will be separately described for purposes of clarity and the interrelationship thereof will be treated accordingly.

The accompanying drawings show preferred 25 embodiments of structures which make possible the practice of the process herein disclosed, the said structures forming the subject matter of separate applications for patent, being a developing unit, a camera unit and a lighting unit, 30 the said applications being identified as follows: Developing machine, Ser. No. 744,886, filed September 21, 1934, Camera, Ser. No. 744,887 filed September 21, 1934 and Photographic lighting system, Ser. No. 744,888, filed September 21, 35 1934.

In accordance with the drawings and the several views thereof, right and left-hand designations refer to the relative position of the operator standing at the rear of the camera and 40 facing the subject.

Figure 1 is a left side view in elevation showing the camera on the inclined runway, the latter being the upper face for the developing unit case-
45 ment.

Figure 2 is a left side view in elevation of the developing unit with the side wall of the case-
50 ment thereof removed showing the housing of the base of the camera and means for the move-
ment of the said housing along the runway.

Figure 3 is a left side view in elevation of the camera structure proper with the side wall there-
of removed.

Figure 4 is a sectional view of Figure 3 along the line 4—4 thereof and shows the bellows 55

front plate and part of the shutter timing mechanism.

Figures 3 and 4 set forth the camera unit structure.

5 Figure 5 is a left side view in elevation of the lighting unit.

Figure 6 is a plan view of the lighting unit.

Figure 7 is an elevational view of Figure 5 along the line 7-7 thereof.

10 Figure 8 is an enlarged and partial medial transverse section along the line 8-8 of Figure 6.

Figure 9 is a plan view of the light housings of Figure 7 along the line 9-9 thereof.

15 Figure 10 is a wiring diagram showing schematically the electrical circuits used in the practice of this system of photography.

Figures 5-10 inclusive as above described, set forth the lighting unit.

20 In accordance with the invention and in accordance with the accompanying drawings, the separate units of the invented system of photography, to wit, the developing unit, the camera unit and the lighting unit are now to be described.

25 *Developing unit*

30 The frame work of the developing unit comprises a plurality of longitudinal base bars 20, front vertical uprights 23, intermediate vertical uprights 24 and rear vertical uprights 25, the said vertical uprights supporting at the tops thereof the inclined upper frame members 22. Intermediate the height of the front vertical uprights 23, there is supported a horizontal shelf 21 within the said frame work. Panels enclose 35 the frame work on the front, rear and side walls, while a base plate is provided to form the flooring of the apparatus, the remaining top opening being covered by movable light proof curtains 136 and 136', the panels and base plates above 40 mentioned not being shown in the drawings specifically by numerals.

45 The mechanism for feeding the previously exposed sensitized paper from the camera unit includes a conveyer 145 being either gravity acting or driven, but in the present embodiment of the invention, the conveyer is represented as being a long trough substantially U-shaped in cross-section and being mounted by hangers 144 and 144', said hangers depending from inclined 50 upper frame member 22, the said conveyer 145 being parallel to the said upper frame member 22. The purpose of the conveyer is to receive a sheet of previously exposed sensitized material, which has been cut and dropped on to the said 55 conveyer by the camera unit. The sensitized material is mounted in the form of a roll in the camera unit, and the cutting results in the production of a definite and uniform size of sheet of sensitized material, the size being adapted to the 60 proportions of the camera and developing units.

The camera unit

65 Cooperating with the above described developing unit is a camera unit. The casing 351 for the camera containing most of the camera elements penetrates and extends at the lower end thereof through a base member 133, the said base member having a top wall cut out for the admission of casing 351, side walls being perpendicular to each other and open at the bottom. The base member is supported by four wheels 134 mounted on the inner surfaces of the longitudinal walls of the base member 133, the bottom edges of the said base member being in a plane 70 parallel to and below the plane of the inclined 75

upper frame members 22. Wheels 134 are provided with flanged portions thereby preventing transverse displacement of base member 133 as wheels 134 ride along the inclined tracks therefore, the latter being formed by inwardly projecting flanges from the upper edges of frame members 22. Numeral 725 indicates two longitudinal and inclined racks affixed to the inner surfaces of inclined frame members 22 at the lower edges thereof, while numeral 726 indicates two spur gears engaging with said racks. The said spur gears are mounted upon a shaft 127, the said shaft being trunnioned at the outer ends thereof in the longitudinal walls of the base member 133. Spur gears 726 mesh with a pair of pinions 728 mounted upon a shaft 129 likewise trunnioned in the longitudinal walls of base member 133. Pinions 728 mesh with smaller pinions 730 mounted upon a shaft 731 trunnioned in longitudinal walls of base member 133 similar to the mounting of shaft 729. Shaft 731 projects through a longitudinal wall of the base member and has affixed at the projecting end a hand wheel 732. It will be seen on Figure 2 whereon one each of the gears 726, racks 725, pinions 728 and 730 are shown, that revolution of hand wheel 732 will cause the base member 133 to ride up and down along the inclined track upon which wheels 134 ride. The manipulation of base member 133 up and down the inclined track is facilitated by means of a counterweight 142 riding within an upright casing 143, the said weight being connected to the base member 133 at the rear transverse wall thereof by a chain 140, the sprocket 141 supporting said chain above the upright casing 143. Situated between the inclined members 22 and below the inwardly projecting flanges thereof are two flexible light proof curtains 136 and 136', the free ends of said curtains being affixed to base member 133 at the rear and front walls thereof respectively, the said curtains 136 and 136' traveling with the movements of base member 133. Curtains 136 and 136' are adapted to ride upon rollers 137, 138 and 137', 138' and the extension and shortening thereof with the movements of base 133 is maintained by the action of spring rollers 139 and 139' respectively to which the ends of the said curtains are affixed.

55 The camera casing 351 containing most of the camera elements is sensitively and manually adjustable after approximate mechanical adjustment and is adapted to be vertically and horizontally adjustable for composition purposes. Journalled in the top wall of base 133 and adapted to move in the plane of the horizontal with plate 733 is a hand wheel 742. Turning hand wheel 742 in either direction raises or lowers camera casing 351 about lugs 739.

60 The actuating means for the horizontal displacement of camera casing 351 comprises a hand wheel journalled on the left side and longitudinal wall of base 133 and designated by numeral 750, the said journalling being at spindle 751.

65 The camera casing for the camera elements designated by numeral 351 comprises forward vertical frame members 352, rear vertical frame members 353 and spaced transverse frame members 354, 355, 356, 357, 358 and 359. All of the said frame members are so disposed as to have 70 affixed thereto an upper and side walls to constitute a light proof casing, the said walls, if desirable being capable or removal for repair purposes. The front wall of casing 351 is provided with an opening for affixation thereto of a bellows 75

chamber. The said chamber comprises an upper plate 362, side plates 363 and 264 and a lower and downwardly inclined plate 365. Numeral 366 designates a motor within the camera casing.

5 The actuating mechanism for the opening and closing of the shutter 491 of the camera proper will now be described. Generally, the shutter is opened by mechanical connection to the armature of an electro-magnet or solenoid 475, the shutter 10 remaining open as long as the solenoid continues to be energized. The electrical circuit to the solenoid is completed through a two-contact brush 540 and a metallic helical segment disposed on the surface of a non-conducting cylinder which 15 begins to revolve at a constant speed with the initial energization of the solenoid. Proper correlation between the duration of the exposure and the spaced position of the lens with respect to the sensitized paper is effectuated by the lens board 20 mechanically controlling the position of the aforesaid brush along the axis of the aforementioned cylinder and in contact with the surface thereof.

Numerals 475 represents a solenoid mounted on 25 the front enclosing panel of the camera casing 351 between the bellows 563 and side wall 364 of the bellows chamber. Numeral 476 represents an armature adapted to be drawn within the said solenoid 475 having an expanded annular flange 30 477 to limit the upward movement thereof. Armature 476 is flattened at the lower end thereof to permit the pivotal attachment therewith of a short link 479 and a long connecting bar 498 by means of the screw 478 thereat. Numeral 600 35 represents a short shaft which penetrates the upper end of a short crank support 484 and also the middle portion of a semi-circularly shaped lever 482, the said support 484 and lever 482 being free to rotate thereabout. Shaft 600 is 40 journaled at the forward end thereof and near the rear end thereof in the upright arms of a U-shaped support 474, the said support being mounted similarly to and directly below solenoid 475 as best seen in Figure 3.

45 Lever 482 is pivotally connected to the lower end of link 479 by a pivot 480. Numeral 564 is a short crank support similar to support 484 while 483 represents a longitudinal crank bar integrally affixed to the lower ends of the supports 564 and 484. End supports 564 and 484 50 together with crank bar 483 comprises a double crank since support 484 is pivotally mounted on shaft 600 and support 564 is pivotally mounted at the upper end thereof to the upper end of 55 an L-shaped upright support 566, the latter being affixed to the forward end of a horizontal support 554. Support 554 is affixed to and projects vertically from frame member 352.

60 Bellows 563 is attached to the periphery of the front panel opening of camera casing 351, the opposite and open end thereof being provided with a plate member 556 to which the forward edges of the bellows are affixed. Plate 556 is provided with a central aperture 473 behind which 65 is mounted a known shutter 491, the said mounting means not being shown on the accompanying drawings. Shutter 491 is provided with an operating trigger 490 pivotally connected at the outer end thereof to the upper end of a link bar 488, 70 the said bar 488 penetrating plate 556 through an aperture 489 therein so that the lower end of the link bar 488 lies forward of the plate 556. The lower end of the link bar is pivotally connected to one end of a lever 485 the other end of 75 said lever being in contact with the upper sur-

face of crank bar 483. Lever 485 is pivotally mounted near the center thereof upon a short stud 486, the said stud projecting forwardly from plate 556. It can be seen that any upward movement of the bar 483 will result in the opening 5 of the shutter 491 as best shown on Figure 4, and since the shutter 491 is set for so-called "bulb action", it will remain open until the bar 483 is allowed to drop.

With an energization of solenoid 475, the circuit to which is completed through a manually controlled shutter release switch 971, the latter not being shown in the drawings except as shown schematically on Figure 10, or a rotary lighting 10 and shutter control switch 830.

15 Directly behind the bellows chamber and within a chamber of the camera casing, there is provided a mirror which is adapted to reflect the image of the subject upon a ground glass having external doors 607 and 608 leading thereto as best shown 20 in Figure 1.

25 The various assemblies comprising the camera structure deriving synchronous motion from the camera motor 366 will now be set forth in functional relationship. With the closing of switch 971 or 830, solenoid 475 is energized thereby allowing the commutator to revolve resulting in the timed opening and closing of the shutter 491 and in the initial energization of motor 366. Motor 366 operates: to feed an exposed portion of 30 the sensitized material into position for a subsequent exposure; to position the previously exposed portion of the sensitized material at the lower edge thereof opposite the counter device; to rotate the commutator thereby closing an auxiliary power circuit to the said motor; to illuminate the counter device and operate the same; to reset the spring mechanism operating the commutator; to sever the exposed portion of the sensitized material from the rolled stock; to open the discharge 35 gates thereby allowing the exposed sheet of sensitized material to fall on the conveyer 145 to the developing unit; to open its own power circuit at the completion of the above enumerated operations.

The lighting unit

40 The lighting unit is supported by a vertical framework comprising three upright members 800 projecting upwardly from the side walls of the developing unit housing, these upright members 45 being joined by a horizontal connecting bar 801 at the upper terminals thereof, the said connecting bar 801 serving as a support for a depending upright member 800', a cross-section of the said four upright members forming the 50 corners of a substantial square. Panels 828 attached to the upright members 800 and 800' from the connecting bar 801 to a point above the camera unit form an enclosure for the control mechanism of the lighting unit.

55 Extending from the connecting bar 801 are two parallel and horizontal frame members 802 adapted to support the main lighting dome and related mechanism as will be more fully described below. The frame members 802 are reinforced 60 by means of two braces 803 extending from the frame members 802 to the forward upright members 800. Horizontal frame members 802 are fixed in position by means of transverse spacers 806" at the forward ends and 806' at the rear 65 ends. Behind spacer 806" is another transverse spacer 804 having mounted thereon by means of studs 805' a parallel reinforcing member 805 while a short distance forwardly of 806' is 70 another similar and parallel spacer 806. Par- 75

allel and below spacer 804 is another cross member 807 depending therefrom by means of studs 807'. Rotatably suspended below cross member 807 by means of a bolt and nut 808 is a plate 809, the said bolt and nut 808 penetrating member 807 and plate 809 through aligned orifices therein. At the outer ends of plate 809 are affixed the upper circular surface 814 of the lighting dome 811 and two spaced parallel bars 810, the said bars 810 being disposed at right angles to plate 809. Plate 809 is rotatably actuated by means of a longitudinal tie bar 816 pivotally connected to one end of said plate, the said tie bar 816 being controlled by a handle 826 situated on a small panel 829, the latter superposing the panel 828 which faces the operator, all as best seen in Figure 5. The motion of handle 826 is communicated to tie rod 816 by means of a shaft having, sprocket 823 thereon, chain 822, thence by mechanism not shown to a gear 818 the latter having a concentric arm affixed thereto 817. Arm 817 at the outer end thereof is pivotally connected to the rear end of the abovementioned tie bar 816. Numeral 821' represents an idler sprocket which is mounted upon a short shaft 824 and serves merely to position the chain 822. Handle 823 is provided with a known position indicator 827.

Lighting dome 811 is provided with a circular upper surface 814, a depending cylindrical surface 813 from the perimeter thereof, a frustum of a cone surface 812 extending outwardly from the lower edge of 813 and a depending cylindrical surface 811' from the lower perimeter of 812. Lowermost cylindrical surface 811' is provided with diametrically opposed openings 811'' and a circular base plate 815 affixed to and extending beyond the lower edge of the cylindrical surface 811'.

Affixed to the under surface of 814 are a series of sockets concentrically arranged to carry bulbs 955.

Affixed to the ends of bars 810 are two spaced and parallel bars 832 and 833 being at right angles to bars 810. At each juncture of these bars, there being four altogether, a vertically depending rod, 834, 835, 836 and 837 fixes the intersection of the cross bars thereat and at the lower end of each rod is provided an orifice. Rods 834 and 835 are connected immediately above the lower extremities thereof by a horizontal spacer 838 through which the said rods penetrate, while 840 represents a horizontal frame member contacting spacer 838 at the lower surface thereof and is penetrated and supported by said rods 834 and 835. Rods 836 and 837 similarly carry corresponding spacer 839 and frame member 841. Numerals 848' and 841' represent guy wires connecting the extremities of frame members 840 and 841 to the bars 810 and serve to support the said frame members. Frame members 840 and 841 are provided at the extremities thereof with depending vertical guide-ways 842, 843, 844 and 845. Guide-ways 842 and 843 together and guide-ways 844 and 845 form race-ways for plates 846 and 846' respectively. Plates 846, 846' carry illuminator housings 851 and 852 respectively, adjacent the upper edges thereof the said housings corresponding in structure and being oppositely disposed. Figure 9 of the drawings shows housing 851 in detail and thus also brings out the details of housing 852. Housing 851 is supported by affixation to the inner surface of plate 846 and constitutes a box-like structure having a removable inner

translucent wall 853 to permit the penetration of light therethrough from incandescent bulbs or light sources 854, 855 and 856 mounted within said housing. Translucent wall 853 may be composed of any suitable substance known in the art such as "opal" glass, or tracing cloth. Projecting rearwardly from and affixed to plate 846 adjacent the lower edge thereof, is a bar 860 carrying at its outer extremity a housing 862 having therein an incandescent bulb 862' and having an inner wall comprising an outer sheet of clear glass 864 and an inner sheet of transparent material 865 having an image thereon. Sheet of glass 864 has the inner surface thereof lightly silvered so that when bulb 862' is not illuminated, sheet of glass 864 acts as a mirror while when bulb 862' is illuminated, the image on transparent material 865 is made visible through sheet of glass 864.

Projecting forwardly and downwardly from and affixed to the inner surface of plate 846 is a bar 847 carrying at the outer end thereof a housing 848 having a bulb 848' therein. Housing 848 positioned below the level of housing 862 as best seen in Figure 7 of the drawings.

Housing 852 together with the appurtenant structure, being the counter part of housing 851 and its appurtenant structure as above described is incompletely shown in Figure 6 whereon 846' represents a movable plate, 857, 858 and 859 30 represent incandescent bulbs, 849 represents a bar carrying a housing 850, 861 represents a bar carrying a housing 863. Plates 846 and 846' are vertically and slidably displaceable and thereby serve to vertically position the housings 35 851, 852, 862, 863, 848 and 850.

Plate 846 has affixed to the upper edge thereof two cables 866' and 869', the said cables being substantially parallel and flexible. Cables 866' and 869' rise vertically turning inwardly about 40 a pair of idler pulleys being positioned at the junctions of frame member 840 and guide-way 842 and frame member 841 and guide-way 843. The said cables continue from the idler pulleys to drums 866 and 869 respectively where they 45 are affixed. Drums 866 and 869 are keyed to a horizontal shaft 870, the said shaft being journaled at the ends thereof in brackets 833' and 832'.

Similarly, plate 846' is provided with cables 50 867' and 868' turning about a pair of idler pulleys positioned at the junctions of frame member 840 and guideway 844 and frame member 841 and guideway 845. The said cables continue from the idler pulleys to drums 867 and 868 respectively where they are affixed. Drums 867 and 868 are keyed to a horizontal shaft 871 journaled at the ends thereof in brackets 833'' and 832''. Brackets 833' and 833'' depend from the forward edge and ends of bar 833 while brackets 60 832' and 832'' depend from the rear edge and ends of bar 832.

Shafts 870 and 871 carry sprockets 872 and 873, respectively, immediately forward of drums 869 and 868, said sprockets being interconnected 65 by a chain 874. Shaft 871 at the forward end thereof which projects forwardly of bracket 833'', carries sprocket 875. The said sprocket 875 is connected by means of a chain 876 to a sprocket which is affixed to the forward end of a short 70 shaft 878. Shaft 878 is journaled at its forward end by penetrating a plate 879, and at its rear end in a bracket 884', the latter depending from the rear edge of reinforcing member 884. The rear end of shaft 878 projects beyond its 75

journal and connects with a universal joint 882, the latter being affixed to the forward end of a shaft 883. Shaft 883 in turn connects with a shaft by means of a pair of bevel gears (not shown), which shaft carries thereon a sprocket which is connected by a chain to a sprocket the latter being carried on a shaft which is journalled by means of orifices in the upper ends of upright members 800, the said upright members being the two forward ones. Said shaft has mounted thereon the drum 893 (see Fig. 5). It is seen from the foregoing mechanism that motion from the drum 893 is communicated to shafts 870 and 871 resulting in the raising and lowering of plates 846 and 846'.

The concentric drum 893 has coiled thereabout a flexible cable 894. One end of cable 894 is affixed to the housing 933 while the other end of said cable is coiled about another drum 895 from which drum the said cable continues and terminates in affixation to the base plate 133 of the camera casing. The disposition of cable 894 is best seen in Figure 5 wherein said cable rises from housing 933, frictionally engages drum 893, proceeds downwardly to frictionally engage drum 895 and then offsets therefrom to run parallel with inclined frame members 22. Drum 895 is concentric with shaft 896, the said shaft 896 being journalled by means of orifices in the two forward upright members 800.

The housing 933 aforementioned is divided into two illuminating chambers by a vertical intermediate wall 934, the said housing having mounted therein four incandescent bulbs 935, 936, 937 and 938, two in each chamber. Motion of the camera casing base 133 is directly communicated to the said housing 933 by cable 894, the motion of said cable also serving to raise and lower housings 851 and 852. Housings 933, 851 and 852, 862 and 863, and 848 and 850 move in unison while the vertical positioning of the said housings is a function of the position of the camera casing base 133. Inasmuch as the base 133 of the camera casing is moved for proper focussing and aiming in relation to the subject, it is seen that the lighting of the subject is thereby automatically controlled by the movement of the housings, the relative positions of the housings having been suitably arranged in a predetermined fashion.

50 Situated within the lighting dome 811 are two known spot lights 897 and 898 being provided with lenses 899 and 900, condensing mirrors 901 and 902, incandescent bulbs 903 and 904 and sockets for said bulbs 905 and 906, respectively. 55 The size of the diverging beam emitted by said spot lights is controlled by the shifting of the sockets within said spot lights by any known means such as linear slots 911 and 912 wherein sockets 905 and 906 are adjustably mounted by 60 means of depending bolts 907 and 908 from the said sockets and nuts therefor 909 and 910. Spot light 897 is trunnioned between the lower ends of vertical rods 835 and 837 by means of trunnions 897' while spot light 898 is trunnioned between the lower ends of vertical rods 834 and 836 by means of trunnions 898'. The spot lights, being thus pivotally mounted, are capable of being tilted in a vertical plane thereby casting the beams of light emitted from the said spot lights 70 897 and 898 upon two screens 943 and 944 respectively, said screens being more fully described below. Projecting forwardly in the plane of the horizontal from the side walls adjacent the rear edge of each of the spot lights 897 and 898 are 75 fingers 913 and 914 respectively. Fingers 913 and

914 are pivotally connected by means of links 915 and 916, the latter being joined at the upper ends thereof, to a link 917. Link 917 is caused to move either up or down by reason of communication of motion from shaft 878 thereto through suitable structure not shown.

By reason of the fact that the spot lights 897 and 898 derive their motion from shaft 878 which latter in turn derives its motion from drum 893 which derives its motion from the movement of the camera base 133, and by reason of the fact that housings 851, 852, 862, 863, 868, 869 and 883 derive their motion also from the movement of the camera base 133, it is therefore seen that movement of all the sources of illumination except bulbs 955, vertically, with relation to the sitter, is synchronized and co-ordinated.

Screens 943 and 944 heretofore mentioned are composed of any suitable flexible material such as cotton or linen and have provided on the inner surfaces thereof a coating of suitable light reflecting and diffusing material such as aluminum paint or dull white paint. Screens 943 and 944 are supported at the upper ends thereof by affixation to and winding about spring rollers 941 and 942, the said screens extending downwardly over direction controlling idlers 945 and 946, 949 and 950 and finally terminating in weighted edges 953 and 954 respectively, all as best seen in Figure 7. Spring rollers 941 and 942 are provided with the usual ratcheting means of ordinary window-shade rollers. In order to raise or lower screens 943 and 944, edges 953 and 954 thereof are manipulated like ordinary window shade rollers. Rollers 941 and 942 are disposed parallel to bars 810 and are mounted upon brackets 939 and 940 respectively, said brackets projecting upwardly from the outer ends of bars 832 and 833. Idlers 945 and 946 are mounted between the upper ends of upright arms 947, and 948, 40 said arms projecting upwardly from frame members 840 and 841 while idlers 949 and 950 are mounted between the outer ends of lateral arms 951, and 952, respectively, said arms projecting laterally and outwardly from guide-ways 842, 45 843, 844 and 845, respectively.

For the connecting and disconnecting of electrical current to the various sources of illumination described hereinabove, a known segmental rotary switch 830 is provided. The said switch 50 830 is mounted upon an auxiliary panel therefor 830' located on panel 828 directly forward to the left of auxiliary panel 829. Switch 830 is operated by means of an operating lever 957 which projects radially from a short shaft 958, the said shaft 55 being journalled in panel 830'. Switch 830 is adapted to successively make and break contact with radially disposed and concentric conducting segments *a*, *b*, *c*, *d*, *e*, *f*, *g*, *h*, *j*, *k*, and *m*, the disposition of said segments being best shown 60 in Figure 10.

Switch 830 in its upper vertical position closes no circuits while by virtue of the staggered arrangement of the segments thereabout, the said switch is capable of seven distinct positions when 65 rotated either left or right of the aforesaid upper vertical position.

Situated directly below and on the same plane with auxiliary panel 830' is another auxiliary panel 831 carrying thereon three known toggle 70 type switches 964, 965 and 966. Switches 964 and 966 each either make or break a single circuit while switch 965 either makes or breaks two circuits simultaneously.

In the operation of the lighting unit, the sub- 75

ject is seated or allowed to stand along the vertical axis of lighting dome 811. At this point in time the operator decides whether a left or right profile of the sitter is desired, or as in the case 5 of the average sitting where a series of different views will be made, either the right or the left profile may be taken first. Assuming that the right profile is to be photographed first, switch 964 is shifted to its "on" position thereby completing a circuit from the electrical line through conductors 967 and 968 to the outlet n. Current travels from outlet n by means of conductors not shown in the drawings to bulbs 904, 936 and 857. The illumination of bulbs 904, 936 and 857 10 lights up the features of the sitter sufficiently for the proper focussing and composition thereof by movement of the camera base member 133. The act of moving the camera base member 133 for focussing and composition purposes effectuates 15 the proper vertical positioning of all the sources of illumination; the lower the position of the camera base member 133 along the inclined runway therefor, the lower is the position of the sources of illumination except for bulbs 955 the 20 position of which is fixed within dome 811. The 25 image of the sitter having been properly focussed the camera is set for exposure.

Rotary switch 830 is moved in a clock-wise direction to its first consecutive "on" position, that 30 is contacting the conducting segment a said movement resulting in completion of a circuit to outlet p through conductor 967, resistor 969, conductors 970, 971 and 968, and also switch 965. Current travels from outlet p by means of conductors not 35 shown in the drawings to bulb 848.

It is understood that the rotation of the lighting dome 811 together with horizontal frame members 840 and 841 and all the mechanism depending therefrom may be effected now or at any 40 time subsequent to the camera focussing of the sitter, the said rotation being accomplished by manipulating handle 826. Handle 826 is rotated until the sitter is able to see his reflection in the mirrored surface in the housing 863, it being 45 understood that all of the above steps are taken for the photographing of the right profile and all the steps hereinbelow until the contrary is stated are for the photographing of the right profile of the sitter. The extent of rotation of dome 811 is 50 controlled by the sitter's seeing his full view in the mirrored surface of housing 863 when looking forward, and in order that the sitter see such full view, the latter gives the operator instructions as to the extent to which the said dome 811 must 55 be moved by means of handle 826. The rotation and final position of dome 811, by reason of the fact that the relative spatial interrelation of the various illuminating sources rotatable therewith has been predetermined relative to housing 863, 60 results in proper illumination of the subject in all planes. The relative spatial interrelation of the various illuminating sources follow the pattern of the approved style for a particular position of the sitter and it is from this pattern that your 65 applicant makes automatic such illumination for different positions of the sitter in the several upright positions and in the several face positions.

The rotation of dome 811 and the rotatable elements therewith results in positioning housing 70 848 so that the head of the sitter is situated between said housing and the lens 493 of the camera. The effect, therefore, of the illumination of bulb 848' is to outline the head of the subject in socalled "backlighting" or in "Rembrandt" style. 75 If these last mentioned effects are not desired,

toggle switch 965 is shifted to its off position thereby opening the circuit to bulb 848.

Switch 830 is now advanced in a clock-wise direction to its second position thereby contacting conducting segment c completing a circuit therethrough to outlet u. Current travels from outlet u through conductors not shown in the drawings to bulb 863' which upon illumination makes the mirrored surface in housing 863 transparent so that the sitter is able to see the image therebehind 10 in said housing. The purpose of illuminating housing 863 at this time is to further attract the attention of the sitter to this point so that his head and eyes may appear properly directed in a finished photograph; furthermore, the subject 15 matter of the image is conveniently alterable by merely substituting different transparencies therein. This device, utilizing known principles of psychological suggestion aids in the inducement of pleasant expression on the sitters countenance. 20

Switch 830 is now advanced in clock-wise direction to its third position thereby contacting conducting segment e completing a circuit therethrough to outlet v. Current travels from outlet v through conductors not shown in the drawings 25 to bulbs 955. Illumination from bulbs 955 is reflected from the upper surface of plate 815 through the openings 811' and is in turn reflected from screens 943 and 944 upon the sitter. Because of the multiplicity of bulbs 955 and the 30 indirection with which the light therefrom reaches the sitter, said light is highly diffused and of sufficiently low intensity so that it constitutes "general" or socalled "atmosphere" illumination.

Switch 830 is now advanced in clock-wise direction to its fourth position thereby contacting conducting segment f completing a circuit therethrough to outlet w. Current travels from outlet w through conductors not shown in the drawings to bulb 935 serving thereby to increase or 40 augment the quantity of illumination being cast by bulb 936 from one of the chambers of the housing 933.

Switch 830 is now advanced in clock-wise direction to its fifth position thereby contacting 45 conducting segment h and completing a circuit therethrough to outlet x whence current travels through conductors not shown in the drawings to bulbs 858 and 859, serving thereby to augment the illumination already being cast by housing 50 852.

Further clock-wise advancement of switch 830 to its sixth position results in contacting conducting segment k thereby completing a circuit through conductors 967 and 969 which short circuits the circuit comprised of resistor 969' and conductor 970. The shortcircuiting of resistor 969' causes all of the light sources which have been receiving current therethrough to increase to their maximum brilliancy so that the combined actinic power of said sources of illumination is of the proper degree with relation to the shutter timing of the camera in the camera unit. It is to be noted at this point that the reason for illuminating the various light sources in successive steps of greater brilliancy rather than to bring them on simultaneously is to avoid excitement, fright, starting and squinting of the sitter. 60 65

Since all of the illuminating sources have been energized as has above been set forth the exposure may be caused to take place by advancing switch 830 in a clock-wise direction to its final and seventh position thereby contacting conducting segment m which closes the circuit to solenoid 475. If the operator desires to leave his 70 75

position adjacent the switch 830 to take a position from which he may better view the facial expression of the sitter, he may leave switch 830 in its sixth position and release the camera shutter by closing switch 971 indicated schematically on Figure 10 of the drawings. Switch 971 is a conventional switch of a type adapted to remain normally in an open circuited position, but which closes while under manual pressure. Said switch 971 is connected to one end of a two-conductor cable of substantial length, and is not shown in the drawings other than as above indicated.

After exposure has been completed, switch 830 is cranked anti-clockwise to its upper vertical position, which extinguishes all of the lights except those receiving current through toggle switch 964.

Where it is desired to photograph the left profile of the sitter, all of the abovementioned operations are repeated, except that they are performed in the opposite direction. Thus toggle switch 964 is shifted to its "off" position, which extinguishes bulbs 904, 936, and 857. Next, toggle switch 966 is moved to its "on" position thereby completing a circuit to outlet o, whence current travels via conductors not shown, to bulbs 903, 937, and 854. Next, the camera is properly positioned along its track, and focussed, in a manner identical with that when the right profile was photographed.

Rotary switch 830 is now moved anti-clockwise to its first consecutive "on" position, thereby contacting segment b and completing a circuit therethrough to outlet q, whence current travels via conductors not shown to bulb 850'. If "back lighting" is not desired, switch 965 is shifted to its "off" position. Handle 826 is now rotated until the sitter is able to see his full head-on image in the mirrored surface of housing 862.

Switch 830 is now rotated anti-clockwise to its second position thereby contacting segment d completing a circuit to outlet t and therethrough via conductors not shown to bulb 862'.

Next switch 830 is moved to its third anti-clockwise position thereby contacting segment e, thus illuminating bulbs 955 as set forth above, since segment e is continuous in both clockwise and anti-clockwise revolutions of arm 959. Switch 830 is then shifted anti-clockwise to its fourth position thereby contacting segment g completing a circuit therethrough to outlet s and thence via conductors not shown to bulb 938. Next, switch 830 is moved anti-clockwise to its fifth position, thereby contacting segment j completing a circuit therethrough to outlet r whence current travels via conductors not shown to bulbs 855 and 856.

When switch 830 is further rotated in an anti-clockwise direction to its sixth and seventh positions, the circuits completed thereby are identical to those which were completed in the sixth and seventh positions in the clockwise rotation thereof since segments k and m are continuous in both vertical halves of the circle.

While as stated hereinabove, the sitter is placed to expose either his right or left profile to the lens of the camera it is to be understood that any intermediate angle may be made by the sitter's head, from full face to absolute profile, and since with the shifting of the sitter's head the corresponding housing 863 or 862 will have to be rotated so that the sitter may see his full face reflected therefrom, it follows that all of the related light sources will be correctly positioned in the horizontal plane.

The intensity of light emitted by housings 851 and 852 is greater than that emitted by housing 933, so that the former 851 and 852 constitute the "drawing" or "accentuating" light sources while the latter 933 constitutes the light source which serves to heighten the tones of the shadow portions of the photograph. Where the sitter sees his reflection in housing 863 and switch 830 is rotated clock-wise or sees his face reflected in housing 862 and switch 830 is rotated anti-clockwise, an approved style of lighting results in which the greater portion of the face seen in the photograph is less brilliantly illuminated than the lesser portion of the face. Where the sitter sees his reflection in housing 862, yet the sitter shows his right side or the right side of his face to the lens and switch 830 is rotated anti-clockwise, or conversely where the sitter turns his head to his right thus showing the left side of his face to the lens, and sees his image reflected from housing 863, and switch 830 is rotated in a clockwise direction, another approved style of lighting results, which is so called "open" lighting. In "open" lighting the greater portion of the face is more intensely illuminated and the lesser portion of the face is less brilliantly illuminated.

Since most of the light which falls on the face of the sitter falls at an angle of approximately forty-five degrees, because of the automatically proper coordination between movement of the camera along its runway, and the vertical positioning of the movable light sources, as has been set forth above, this system is capable of many other approved styles of lighting which will always be basically correct. In the hands of a skilled operator, the versatility of the lighting system is readily seen. By studying the image of the sitter in the groundglass handle 826 may be turned at random until a pleasing effect is produced, and since the rotation of switch 830, for the most part, serves to increase the intensity of the light sources, rather than inaugurate new ones, composition decided upon at low intensity will retain its quality when the illumination is sufficiently intense for exposure.

In the hands of an unskilled operator, this lighting system may be operated so that very little judgment is required. For normal lighting effects, vertical positioning of the light sources is fully automatic, while horizontal positioning is accomplished by merely turning handle 826, until the sitter can see both of his ears in the proper reflecting housing, either 862 or 863. Where it is desired to have an unskilled operator duplicate unusual effects, these may be originally determined by a skilled operator, and all the unskilled operator need do is follow explicit instructions involving very little judgment. Dial 827 being accurately calibrated, he need only manipulate handle 826 until the pointer coincides with a certain calibration marking on the dial. In this manner, a good lighting style once conceived may be reexecuted at will.

Where the subject is possessed of unusually fair complexion or light hair, proper lighting may be simply obtained by shifting switches 964 or 966 to their "off" position. In that case, composition and focussing is performed before this is done or focussing is performed with switch 830 advanced in either direction the requisite number of steps.

It will now be observed that the system of photography hereinabove described comprises the combination of three units, a camera unit, a de-

veloping unit and a lighting unit. In each unit there are assemblies and sub-assemblies which are novel by themselves; while in the combination of the three units or in the combination of any two units novelty resides. There exists novelty in the combination of the elements from one unit with elements of each of the other units.

I wish it distinctly understood at this time that the mechanisms described in the above specification to accomplish certain movements were conventional and that such mechanisms are not to be construed as limiting the scope of the invention; minor changes and variations in the integration of several parts of each unit and in the parts themselves may be resorted to without departing from the spirit of the invention; minor changes and variations in the means of transferring motion and in the synchronization of the several parts of each unit and in the units themselves may be resorted to without departing from the spirit of the invention; and lastly, minor changes and variations in the means to accomplish the defined results hereinbefore developed may be resorted to without departing from the scope of the invention and without departing from the scope of the appended claims.

I claim:

1. In a system of photography, tracks, a camera movable on said tracks, the motion having horizontal and vertical components, a casing supporting said tracks, means of light-proof communication between the camera and the casing whereby exposed sheets of sensitized material from the camera are dischargeable at all positions of the camera into the said casing, and lighting means mounted independently of the said camera and means to regulate said lighting means in correlation with the movement of the said camera.

40 2. In a system of photography, a camera movable in a direction having vertical and horizontal components, lighting means mounted independently of the camera and means to regulate said lighting means in correlation with the movement of said camera.

45 3. In a system of photography adapted for use with a subject: tracks, a camera movable on said tracks in a direction having vertical and horizontal components, a casing supporting said tracks, means of light-proof communication between the camera and the casing whereby exposed sheets of sensitized material from the camera are dischargeable at all positions of the camera into the said casing, and lighting means mounted independently of the said camera and being pivotally and concentrically movable with relation to said subject and means to regulate said lighting means vertically in correlation with the movement of the camera.

60 4. In a system of photography, a camera, means to move the same in a direction having vertical and horizontal components, a casing supporting said means, means of light-proof communication between the camera and the casing whereby exposed sheets of sensitized material from the camera are dischargeable at all positions of the camera into the said casing, lighting means mounted independently of the said camera and means to regulate said lighting means in correlation with the movement of the said camera.

65 5. In a system of photography adapted for use with a subject: inclined tracks, a camera movable on said inclined tracks, a casing supporting said tracks, means of light-proof communication between the camera and the casing

whereby exposed sheets of sensitized material from the camera are dischargeable at all positions of the camera into the said casing, lighting means mounted independently of the said camera and being pivotally and concentrically movable with relation to said subject and means to regulate said lighting means vertically by movement of the said camera.

6. In a system of photography adapted for use with a subject: a camera, means to move the same in a direction having vertical and horizontal components, a casing supporting said means, means of light-proof communication between the camera and the casing whereby exposed sheets of sensitized material from the camera are dischargeable at all positions of the camera into the said casing, and lighting means mounted independently of the said camera and being pivotally and concentrically movable with relation to said subject.

7. In a system of photography adapted for use with a subject: tracks, a camera vertically and horizontally movable on said tracks, a casing supporting said tracks, means of light-proof communication between the camera and the casing whereby exposed sheets of sensitized material from the camera are dischargeable at all positions of the camera into the said casing, lighting means mounted independently of the said camera and being pivotally and concentrically movable with relation to said subject and means to regulate said lighting means vertically by movement of the said camera.

8. In a system of photography adapted for use with a subject: inclined tracks, a camera movable on said tracks, a casing supporting said tracks, means of light-proof communication between the camera and the casing whereby exposed sheets of sensitized material from the camera are dischargeable at all positions of the camera into the said casing, and lighting means mounted independently of the camera and being pivotally and concentrically movable with relation to said subject and automatically regulable by movement of the said camera.

45 9. In a system of photography adapted for use with a subject: inclined tracks, a camera movable on said tracks, a casing supporting said tracks, means of light-proof communication between the camera and the casing whereby exposed sheets of sensitized material from the camera are dischargeable at all positions of the camera into the said casing and lighting means mounted independently of the camera and being pivotally and concentrically movable with relation to said subject.

10. In a system of photography for use with a subject: inclined tracks, a camera movable on said inclined tracks, lighting means pivotally and concentrically movable and being mounted independently with relation to said subject of the camera.

60 11. In a system of photography, tracks, a camera movable on said tracks, lighting means mounted independently of the said camera and means to regulate said lighting means in correlation with movement of the said camera.

65 12. In a system of photography for use with a sitter, a camera, means to move the same in a direction having vertical and horizontal components, illumination sources, mechanism to regulate said sources vertically in correlation with the movement of said camera and means to pivotally and concentrically move said illumination sources with relation to said sitter.

13. In a system of photography for use with a subject capable of rotational displacement: a camera, means to move the camera in a direction having horizontal and vertical components, illumination sources, means to move said illumination sources pivotally and concentrically about said subject as a pivotal center and means to correlate the rotational displacement of said illumination sources with rotational displacement of said subject. 5
14. In a system of photography for use with a subject, a camera, means to move the same in a direction having vertical and horizontal components, and illumination sources pivotally and concentrically movable with relation to said subject. 10
15. In a system of photography for use with a subject capable of rotational displacement: tracks, a camera movable on said tracks, illumination sources vertically regulable by movement of said camera, means to move said illumination sources pivotally and concentrically about said subject as a pivotal center, means to correlate the rotational displacement of said illumination 20 sources with rotational displacement of said subject, and means to light up the desired illumination sources in predetermined combination." 25
16. In a system of photography, a camera movable on said tracks, illumination sources and reflector means therewith pivotally and concentrically arranged about said subject, means of automatically regulating the vertical displacement of the said illumination sources by movement of the 30
- said camera, and means to light up the desired illumination sources in a predetermined combination. 5
17. In a system of photography for use with a subject in an illuminated field: a camera movable in a direction having horizontal and vertical components, and illumination sources pivotally and concentrically movable as a unit with relation to said subject and producing said field of illumination. 10
18. In a system of photography, a movable camera, lighting means movable independently of the camera, means to move the lighting means in predetermined correlation with the movement of said camera. 15
19. In a system of photography, a movable camera, lighting means movable independently of the camera, means to correlate the vertical movement of said camera and said lighting means, whereby the vertical movement of said camera 20 and the vertical movement of said lighting means are mutually dependent in predetermined interrelation. 25
20. In a system of photography adapted for use with a subject, a movable camera, lighting means movable as a unit independently of said camera, means to correlate the movement of said camera and said lighting means whereby a predetermined movement of one causes a predetermined movement of the other, said lighting means 30 being also capable of an independent pivotal and concentric movement about said subject. 25

SAMUEL HERSHBERG.
